TYPEWRITING MACHINE

John L. Petz, Rochester, N. Y., assignor to International Business Machines Corporation, New York, N. Y., a corporation of New York.

Application September 19, 1936, Serial No. 101,543

6 Claims. (Cl. 197—186)

This invention relates to typewriting machines in general and more specifically to the framework.

The object of the invention is to provide an improved framework for supporting such parts as the key levers and sub-levers.

An object is to provide a support frame which is light and cheap to manufacture, yet is rigid and sturdy and maintains the parts supported, such as the sub-levers, accurately and permanently centered with respect to other parts of a typewriting machine.

Another object is to provide a support frame which does not require for its manufacture the use of complex tools, such as gang milling cutters and intricate fixtures.

An object is to provide a supporting frame, the principal parts of which may be made by simple stamping or drawing operations.

Various other objects, advantages, and features will be pointed out in the following description and claims, or will be apparent from a study of the description, claims, and accompanying drawings.

25 In the drawings:

Fig. 1 is a vertical section through a power type bar operating mechanism incorporating the frame comprising the present invention.

Fig. 2 is an enlarged view of certain parts shown in Fig. 1.

30 Fig. 3 is a plan view of the frame comprising the present invention.

Fig. 4 is a perspective view of the frame formerly used.

35 The present invention has been shown as applied to the well-known "International" electric writing machine which was formerly known in the art as the "Electromatic." In this machine there is provided the paper carriage 10, in which is mounted the usual platen 11 for supporting the work sheet, which carriage is mounted by means of anti-friction bearings 12 on the usual grooved guide rails 13. The escapement mechanism, generally designated 14, controls letter spacing movement of carriage 10 in writing upon the work sheet supported by platen 11.

40 The type bars 15 are pivotally mounted in the wire segment 16 forming part of the type basket 17. A universal bar 18 in the form of an open frame is arranged to be operated by movement of the type bars 15 to printing position and actuates the escapement mechanism by means of a link 19 and a lever 20. A toggle, comprising a toggle lever 21 and a toggle link 22, connects 45 each of the type bars 15 with a pivot rod 23

mounted in segment 17. A link 24 connects each toggle lever 21 with a sub-lever 25 pivoted on a fixed rod 26. This rod also serves as a pivot for the controlling keys 27 and for a key lever like 28 which is connected to and actuated by the 5 space bar 29. Each sub-lever 25 is mounted alongside the key 27 which corresponds to the type bar to which the sub-lever is connected.

The sub-levers 25 are operated in a well-known way by cam units 30 cooperating with a power 10 roller 31 which turns in the direction of the arrow in Fig. 1. Each cam unit is pivoted on a rod 32 and is connected by a link 33 with a sub-lever 25. There is a cam unit 30 for each key 27 and one for the lever 28 associated with the 15 space bar. When a key is depressed, the associated cam unit is operatively engaged with the power roller 31 causing the cam unit to rock on its pivot 32 in a direction to draw downwardly the proper link 33, thereby rocking the sub-lever 25, 20 connected to such link in a clockwise direction (Fig. 1). The link 24 is thereby drawn to the right, bending the toggle 21, 22 and operating the type bar corresponding to the key 27 which was depressed. The cam unit for the space bar 25 does not operate a type bar, but operates escapement 14 through a train of connections not shown.

Heretofore it has been the practice to support the pivot wire on a frame very similar to the one shown in perspective in Fig. 4. This frame consisted of two parts, a member 34 made from a flat strip of heavy gauge steel bent longitudinally to form an obtuse angle in transverse section, and a member 35 consisting of a second and considerably thinner strip bent to a U-shape in transverse section and welded to both sides of member 34 along one edge thereof. The member 34 is slightly thicker than the pivot rod 26 and the bend in member 35 is the same in diameter as the thickness of member 34 and is spaced from 30 the welded edge of said member a distance sufficient to allow the pivot rod to be slid freely into the space thus formed by members 34, 35. After the members 34, 35 have been welded a plurality of equally spaced slots 36 are cut in 35 both members as shown in Fig. 4, each slot being wide enough to accommodate one sub-lever 25 and its corresponding key 27. The composite frame 34, 35 is at its ends mounted on two posts 50 like 37 (Fig. 3) formed in a sub-frame 38 which also supports the pivot wires 32 for the cam units 30. Two screws like 39 and a dowel pin like 40 (Fig. 3) at each end of the frame 34—35 secure the frame to said posts. The holes for 55

these screws and dowel pins are clearly shown in Fig. 4.

The form of construction shown in Fig. 4 has been found by experience to be not completely satisfactory from a manufacturing standpoint due to the cost of maintaining accurate spacing of the slots and certain other difficulties encountered in the process of manufacture. In order to manufacture the frame at a reasonable cost it is necessary to mill the slots 36 by means of a gang cutter having a separate cutter for each of the slots, as it is too costly to make a one-piece cutter with a row of teeth for each slot and both costly and too slow to mill the slots one at a time. A rather expensive milling fixture is required to be used with the gang cutter in order to provide the necessary solid support for the material between the slots while they are being cut. When the gang cutter becomes dull all the individual cutters must be sharpened to the same diameter to ensure uniformity in the depth of the slots. Due to the thinness of the material of which the frame 34-35 is made, heavy burrs are formed at the ends and to a certain extent at the sides of the slots 36 and these burrs are difficult, as well as expensive, to remove. Other difficulties are also experienced in manufacturing the frame 34-35 as any one experienced in making small machine parts will readily appreciate.

It is desirable that the frame 34-35 be as light and compact as possible in order to reduce the weight and size of the machine. At the same time, since the frame has to support at least 49 key levers and about the same number of sub-levers, it is necessary that the frame be very rigid to resist deflection of the pivot rod due to the weight of parts supported by the frame and the deflection forces produced by the operation of the sub-levers by the cam units. It is also necessary that the frame 34-35 be rigid enough to maintain the spacing of the rods 25, 32 as any appreciable variation in the spacing of these rods results in uneven impressions of the type bars.

In order to avoid the manufacturing difficulties and still retain the desirable features stated above, a novel support frame has been devised which is shown in Figs. 1 to 3. This frame consists of a main support member 41 and a plurality of hangers 42. The member 41 is stamped from sheet metal of somewhat lighter gauge than the member 34 in Fig. 4 and is mounted on the posts 37 in the same manner as frame 34, that is, by means of screws 39 and dowel pins 40, as shown in Fig. 3. In order to stiffen the member 41 longitudinally, a rib 43 (Fig. 2) is formed centrally of said member. The frame member 41 is further stiffened longitudinally by bending the longer edges downwardly at right angles to the top surface. The edges of the flanges 44 thus formed are further bent outwardly away from the central rib to form two support flanges 45 for the hangers 42.

The hangers 42 have the general shape of an inverted oblique triangle with the vertices rounded and with the bases parallel with the top surface of member 41. At each end of the base of the triangle, the hangers 42 are so shaped as to provide hook-shaped lugs 46 which embrace the flanges 45 and are soldered or welded thereto. The hangers 42 are spaced equal distances along the member 41 and provided with holes to accommodate the pivot rod 26. While Fig. 3 shows only eight of these hangers or bearing supports,

it is obvious that the number used is purely arbitrary.

There is a group comprising seven key levers 27 and seven sub-levers 25 (Fig. 3) between two adjacent hangers 42, each sub-lever 25 being mounted alongside the corresponding key lever 27, with the sub-levers of the adjacent key levers by a washer 47 of substantially the same thickness as the width of the material between the slots 36 in Fig. 4. The hangers 42 have a thickness approximately half the width of the material between the slots 36 in Fig. 4, therefore washers 48 of substantially half the thickness of washers 47 are interposed between the right hand faces of the hangers and the adjacent sub-lever 25 in order to make the spacing of the groups of key levers and sub-levers equal to the spacing of the slots 36 in Fig. 4.

The holes for screws 39 and dowel pins 40 in member 41 have the same spacing both with reference to each other and with reference to the pivot rod 26 as in the frame 34-35 in Fig. 4 so that the frame assembly comprising members 41 and 42 is completely interchangeable with the frame 34-35.

It will be noted that none of the parts used in the frame shown in Figs. 1 to 3 require milling operations but are simple stamped parts not requiring elaborate dies, tools, or fixtures for their manufacture. Thus the frame may be made cheaply and yet be rigid enough and accurate enough to support the keys and key levers. The thin washers 48 may be stamped from strip stock while the thick washers 47 may be turned from screw stock, both of which are cheap operations to perform on a quantity production basis. There is no problem of burr removal as the slight burrs that may be produced in making the parts of the frame can be easily removed by machine very cheaply.

While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A supporting frame for typewriting machines, comprising a main elongated member formed from sheet metal with a central longitudinal stiffening rib and marginal longitudinal stiffening flanges, and a plurality of hangers mounted at spaced intervals longitudinally of the main member, said hangers being composed of flat sheet metal stampings provided with lugs to engage the edges of the marginal flanges in the main member and extending at right angles to the longitudinal axis of the main member, said hangers being provided with aligned openings for supporting a pivot.

2. A supporting frame for typewriting machines comprising a main support member which is elongated in shape and provided with longitudinal marginal stiffening flanges and a plurality of hangers secured to and interlocking with the edges of said flanges at spaced intervals longitudinally of the main member and provided with aligned pivot supporting holes.

3. A supporting frame for typewriting machines comprising a main support member which is elongated in shape and provided with longi-

5 longitudinal marginal stiffening flanges and a plurality of hangers secured to said flanges at spaced intervals longitudinally of the main member, said hangers comprising flat stampings having a roughly triangular shape extending at right angles to the main member and adapted to support a pivot at spaced intervals along the main member, said stampings having lugs formed therein interlocking with the edges of the flanges.

10 4. A support frame for the key levers and sub-levers of a typewriting or other machine having typewriting mechanism, comprising an elongated main member formed from a single sheet metal blank and provided with longitudinal divergent 15 marginal flanges, and a plurality of pivot supports secured to the divergent marginal flanges at spaced intervals longitudinally of the main member between which supports the key levers and sub-levers are supported.

20 5. A support frame for typewriting machines

comprising a main frame member formed of a single strip of sheet metal with longitudinal marginal stiffening flanges extending in planes at an angle to the plane of the body of said member, said flanges being further provided with divergent longitudinal flanges, and a plurality of pivot supports secured to the divergent flanges at right angles to the longitudinal axis of the main member.

6. A support frame for typewriting machines 10 comprising an elongated main member provided with longitudinal flanges extending at an angle to the plane of the bulk of said member, said flanges being further provided with flanges extending parallel with the plane of the bulk of said member, and a series of pivot supports extending at right angles to the plane of the bulk of said member and secured to the second-named flanges. 15
